UNITED STATES PATENT OFFICE.

JOHN B. F. GAY, OF FITCHBURG, MASSACHUSETTS, ASSIGNOR TO THE
FITCHBURG STEEL BALL COMPANY, OF SAME PLACE.

DIE FOR AND METHOD OF SWAGING METALLIC BALLS.

SPECIFICATION forming part of Letters Patent No. 611,574, dated September 27, 1898.

Application filed August 16, 1897. Serial No. 648,348. (No model.)

To all whom it may concern:

Be it known that I, JOHN B. F. GAY, a citizen of the United States, residing at Fitchburg, in the county of Worcester and State of Massachusetts, have invented a new and useful Improvement in Dies for and Methods of Swaging Metallic Balls, of which the following is a specification, accompanied by drawings, forming a part of the same, in which—

10 Figure 1 represents a plan view of one of the dies. Fig. 2 is a sectional view of the same on line 2 2, Fig. 1. Fig. 3 is a sectional view of the same on line 3 3, Fig. 1. Fig. 4 represents a central vertical sectional view of 15 a pair of dies with a portion of a rod or bar having a series of balls swaged therefrom and inclosed between the dies. Fig. 5 is an enlarged sectional view of the dies through the center of one of the recesses on line 3 3, Fig. 1. 20 Fig. 6 is an enlarged sectional view of the dies through the center of the series of recesses on line 2 2, Fig. 1; and Fig. 7 represents a rod with a series of balls partially formed thereon.

Similar letters and reference-figures refer 25 to similar parts in the different figures.

My invention relates to the dies for and method of swaging metallic balls from rods or bars, and it has for its object to simultaneously swage a series of balls from a single 30 rod or bar; and it consists in subjecting the rod or bar to successive blows between a pair of peculiarly-shaped dies, whereby a series of circumferential grooves are formed in a rod, dividing it into sections, and each of said sections is upset by crowding the metal lengthwise of the rod into spherically-shaped recesses, said rod having been previously selected of a suitable diameter with reference to 35 the distance between said circumferential grooves and less than the required diameter of the swaged ball, so that the metal contained in each section shall be just sufficient to form a ball; and it further consists in providing means for the lateral expansion of the metal 40 in each section of the rod and in rotating the rod relatively to the dies during the operation of swaging in order to bring the swaged rod into circular form at any of its cross-sections.

My invention is particularly designed to 45 swage balls which when ground into absolute sphericity are employed as friction-balls in

the bearings of bicycles and vehicles and in ball-bearings generally. In this class of product it is of the utmost importance that the balls when finished should be true spheres 55 and be of homogeneous texture without flaw and of uniform hardness.

In the manufacture of metallic balls heretofore the swaging has usually been accomplished by rolling, and when it has been done 60 by hammering two operations with two sets of dies have been required, one for "breaking down" the rod and the other for shaping the ball, and it has not been deemed practicable to swage more than a single ball at each 65 operation, making the manufacture by the process of hammering slow, expensive, and wasteful of material. When the balls are shaped by the operation known as "drop-forging" or by the compression of the metal 70 by a single heavy blow between dies of the desired shape, a projecting fin is formed around the ball which must be cut or ground away, requiring a separate operation and destroying the homogeneity of the surface of the ball. 75 I have overcome these objections by simultaneously swaging a series of four or more balls at a single operation by means of the swaging-dies and the method hereinafter described, whereby the forged balls are approximately 80 spherical, of homogeneous texture, and without projecting fins.

In the accompanying drawings, A denotes the upper, and B the lower, die of a pair of dies by which my invention is carried into 85 practice, said dies being duplicates so far as their working faces are concerned. The lower die B is preferably employed as the stationary die or anvil, and the upper die A is reciprocated by any suitable connected mechanism. (Not shown.) The dies represented in the accompanying drawings are adapted to swage a series consisting of four balls; but the number can be increased or diminished, if desired, the balls being connected together 95 by a slender neck which allows the balls to be rotated between the dies and readily separated in order to detach them and grind them into true spherical shape. In Fig. 1 I have represented the face or working side of the 100 lower die, the upper die being a duplicate thereof, having four recesses 1 2 3 4. The

recesses are duplicates, and each consists of an elliptical opening in the face of the die, having its minor axis 5 coincident with the line 2 2, Fig. 1, and corresponding with the 5 diameter of the ball, and its major axis 6 transverse thereto and longer than the diameter of the ball and having the curved bottom 7 preferably spherical, corresponding with the size of the ball to be swaged.

10 Each division-wall 8 between the recesses is hollowed in the center to afford space for necks 9, connecting the balls, the edge 10 of the division-wall forming a curved line having a radius much greater than the diameter 15 of the neck 9. The division-walls 8 are beveled between their curved edges 10 and the spherical bottoms 7, as at 11, in order to form a dull edge and make the walls wedge-shaped in their cross-section, as shown at 12 in Figs. 20 4 and 6.

The outer side walls 13 14 of the outer recesses 1 and 4 are shaped similar to the division-walls 8 by means of recesses 15 16, formed in the sides of the die. The curved 25 bottom 7 of each recess is connected with the ends of the elliptical opening by curved surfaces 17 17, which are preferably tangential to the curved bottom 7.

In the operation of swaging balls by my 30 improved dies I employ a rod or bar 18 whose diameter is slightly less than the desired diameter of the ball to be swaged. The size of the rod is determined by making it of such diameter that the metal contained between 35 the adjacent edges 10 of the dies will be just sufficient to form a ball of the required diameter and a connecting-neck. The rod is inserted between the dies, with its end against a gage 19, which allows the end of the rod to 40 project slightly beyond the side of the die, thereby forming a stub end 20 when the swaging is completed. The first blows of the reciprocating die upon the rod are received by the wedge-shaped walls 12, causing the rod 45 or bar to be upset and the metal to be moved longitudinally toward the center of the recesses and at the same time expanded laterally. The rod is turned during the process of hammering, so that the metal which is 50 expanded laterally in a horizontal plane is brought into a vertical plane during succeeding blows and is crowded toward the center of the recess.

The operation of swaging a series of balls 55 by means of my improved invention is as follows: A rod of the proper size to supply the requisite metal between adjacent edges 10 10 of the dies and having its diameter slightly less than the required diameter of the ball is 60 inserted between the dies A and B, with the end of the rod projecting slightly beyond the sides of the dies, as determined by the position of the gage 19. The reciprocating upper die A is then set in motion and the blows delivered upon the rod are received by the edges 65 10 of the wedge-shaped walls 12, making de-

pressions in the upper and lower sides of the rod which, as the rod is rotated, form grooves 21, Fig. 7. The beveled sides 11 of the recesses crowd the metal in the direction of the 70 length of the rod and toward the centers of the recesses, increasing the diameter of the rod, as at 22, Fig. 7, and at the same time expanding the rod laterally, making it oval in cross-section, the continued turning of the 75 rod during the process of swaging reducing its oval cross-section to a circular cross-section and upsetting the rod by crowding the metal against the curved bottom 7 of the recesses. As the curved edges 10 have a much 80 larger radius than the diameter of the rod, the lateral expansion of the metal in the necks 9 is received in the spaces 23 at the opposite sides of the rod, and by making the axis 6 of the elliptical opening greater than the axis 5 85 I provide similar spaces 24 to permit the lateral expansion of the balls 25. If these spaces were not provided, the metal would be expanded between the faces of the dies, producing what is known as a "fin" upon the sides 90 of the necks 9 and balls 25, with the liability of forming seams or hammering minute particles of iron into the body of the ball, thereby preventing it from being homogeneous.

The curved bottom 7 shapes the metal as 95 it fills the recess into a globular form sufficiently accurate to enable it to be reduced to a true sphere by the operation of grinding, and the connecting-necks between the balls allow the rod and balls to be turned during 100 the operation of swaging for the purpose of bringing the laterally-expanded metal into a vertical plane, in which it becomes compressed.

I do not confine myself to the specific contour or curvature of the bottom of the recess, so long as the minor axis 5 corresponds approximately with the diameter of the ball and the major axis 6 is longer than the diameter of the ball, whereby each blow of the dies 110 tends to shape the ball into a sphere in central cross-section parallel with the axis of the rod and into an oblate or oval form in cross-section at right angles with the axis of the rod.

What I claim as my invention, and desire 115 to secure by Letters Patent, is—

1. A pair of dies for simultaneously swaging a series of metallic balls from a rod, each of said dies having a series of opposing oval recesses in the working faces of the dies arranged with their minor axes in alinement, each pair of adjacent recesses being separated by a dividing-wall presenting a wedge-shaped edge by which the rod is grooved and upset longitudinally, substantially as described. 125

2. A pair of dies for simultaneously swaging a series of metallic balls from a rod, each of said dies having a series of opposing oval recesses in the working faces of the dies, arranged with their minor axes in alinement 130 and approximately equal to and with their major axes greater than the diameter of the

ball to be swaged to provide for the lateral expansion of the ball as it is compressed between the dies, substantially as described.

3. A pair of dies for simultaneously swaging a series of balls from a rod, each of said dies having a series of opposing oval recesses in the working faces of the dies, with their minor axes in alinement, each pair of adjacent recesses being separated by a wedge-shaped wall, by which a groove is formed in the rod, each of said wedge-shaped walls being slightly hollowed to form a lenticular space for the neck of the ball when the dies are brought together, substantially as described.

4. A pair of dies for simultaneously swaging a series of metallic balls from a rod, said dies having a series of opposing oval recesses in their working faces, with their minor axes in alinement and approximately equal to the diameter of a ball, with the bottom of each recess semicircular in the cross-section of its minor axes and curved in the cross-section of its major axes, whereby a spherical form is imparted to the ball by the rotation of the rod as it is successively compressed by the dies without the formation of a fin, substantially as described.

5. A pair of dies for simultaneously swaging a series of balls from a rod, each of said dies having a series of opposing oval recesses arranged in the working faces of the dies, with their minor axes in alinement and approximately equal to, and with their major axes greater than the diameter of the ball to

be swaged, with each adjacent pair of recesses separated by a wedge-shaped wall slightly hollowed to present a curved edge, shorter than the major axes of the recesses, said recesses having curved bottoms, whereby a spherical shape is imparted to the balls, substantially as described.

6. The within-described method of simultaneously swaging a series of balls from a rod, and consisting in swaging a rod of less diameter than the required diameter of the balls to be swaged between a pair of dies, having a series of opposing oval recesses in their working faces, with their minor axes in alinement and approximately equal to, and with their major axes greater, than the required diameter of the swaged ball, said recesses having curved bottoms, with each pair of adjacent recesses in each die separated by a wedge-shaped wall slightly hollowed to form a lenticular space, when the dies are brought together, and rotating said rod a partial revolution between successive blows of the dies, whereby the rod is upset longitudinally by the formation of V-shaped grooves and expanded laterally into spaces provided by said oval recesses which shape the metal between the wedge-shaped walls into a spherical form, substantially as described.

Dated this 7th day of August, 1897.
